UNITED STATES PATENT OFFICE

138,838

DESIGN FOR A BOX COVER OR THE LIKE

Daniel J. Faraggi, Brooklyn, N. Y.

Application January 22, 1944, Serial No. 112,298

Term of patent 7 years

(Cl. D58—12)

To all whom it may concern:

Be it known that I, Daniel J. Faraggi, a citizen of the United States, residing in the Borough of Brooklyn, county of Kings, city and State of New York, have invented a new, original, and ornamental Design for a Box Cover or the Like, of which the following is a specification, reference being had to the accompanying drawing, forming a part thereof, in which:

Fig. 1 shows a plan view of a box cover or the like embodying my new design; and

Fig. 2 is a transverse, vertical section taken substantially through the center thereof.

The essential features of my design reside in the full line illustration in Fig. 1. While I have shown my design in the form of a box cover, it is understood that the same may be embodied in other similar articles without departing from the spirit of my invention.

I claim:

The ornamental design for a box cover or the like, as shown and described.

DANIEL J. FARAGGI.
